UNITED STATES PATENT OFFICE.

FLOYD AUGUSTUS CANTWELL, OF IRVING, KANSAS.

SWITCH-STAND.

1,366,356.

Specification of Letters Patent. Patented Jan. 25, 1921.

Application filed January 2, 1920. Serial No. 348,737.

To all whom it may concern:

Be it known that I, FLOYD AUGUSTUS CANTWELL, a citizen of the United States, and a resident of Irving, in the county of 5 Marshall and State of Kansas, have invented certain new and useful Improvements in Switch-Stands, of which the following is a specification.

My invention relates to improvements in 10 switch-stands.

An important object of the invention is to provide an improved switch-stand in which the signaling means or target is in position to indicate danger at all times, except when the operating parts of the switch-stand are locked in position to maintain the switch points set for main line.

Another object is to provide an improved switch-stand of this character of simple and 20 durable construction, reliable and efficient in operation, and comparatively easy and inexpensive to manufacture.

Other objects and advantages reside in the certain novel features of the construction, 25 arrangement, and combination of parts as will become apparent as the description proceeds, reference being had to the accompanying drawings forming a part of this specification, and in which—

30 Figure 1 is a front elevational view of the improvement showing the parts locked in position to maintain the switch set for main line and the target in clear;

Fig. 2 is a plan view showing the parts 35 in intermediate position, the target being shown in danger;

Fig. 3 is a fragmentary front elevational view showing the parts in intermediate position, portions broken away and shown in 40 section for the sake of illustration;

Fig. 4 is a transverse sectional view on line 4—4 of Fig. 3;

Fig. 5 is a detail view in side elevation, 45 of the operating levers, parts being shown in section for the sake of illustration;

Fig. 6 is a transverse sectional view on line 6—6 of Fig. 5;

Fig. 7 is a transverse sectional view on line 7—7 of Fig. 5;

50 Fig. 8 is a fragmentary detail perspective view of the target operating lever; and

Fig. 9 is a detail perspective view of the target spool and associated structure.

Referring to the drawing it will be seen 55 my invention contemplates a switch-stand including a base 10 which is supported upon

the ties, not shown, on any suitable foundation adjacent the switch in a manner well-known in the art. A table 12 is supported upon the base 10 by the standards 11 and 60 the table is provided with a bearing 13, see Fig. 3, for receiving the vertical shaft 16 and with spaced peripheral notches 14 and 15 for receiving the pivotal lock arm 20 of the switch rod operating lever, all to be 65 hereinafter more fully described.

Journalized in the bearing 13 of the table is the vertical switch rod 16, having a crank 17 at its lower end for connection with the connecting rod (not shown), which operates 70 the switch points to set them for the siding or for the main line in the well-known manner. A switch operating lever 18 is keyed to the vertical shaft 16, as shown at 18' in Fig. 6, the shaft 16 being thus constrained 75 to rotate with the operating lever 18. The outer end of the operating lever 18 is forked as shown at 19 to receive the inner end of the pivoted lock arm 20, which is pivotally connected to the operating lever 18 by a 80 pivot pin 21. Vertically upstanding stop pins 22 arranged slightly more than a quadrant apart on the table 12 limit the movement of the operating lever 18 and also the shaft 16. These stop pins 22 are preferably 85 formed integral with the table 12 and are spaced slightly from the notches 14 and 15, as clearly shown in Fig. 2. By virtue of the lateral extent of the vertical operating lever 18, when this lever abuts against either of 90 the stop pins, the pivoted lock arm 20 is disposed over either the notch 14 or 15 and may therefore be dropped or swung downwardly into the respective notch.

A spool, indicated generally at 23, is 95 loosely mounted on the shaft 16 and as shown in detail in Fig. 9 consists of a hub 24 having an integral lower flange 25 and an integral upper flange 26. The upper flange 26 is provided on its under side with 100 a radially disposed cutaway portion or notch 27, the walls of which are vertical, as shown, and the lower flange 25 is provided on its upper surface with a cutaway portion or notch 28. The notch 28 is slightly 105 spaced about the circumference of the spool from the notch 27, and in the present embodiment of the invention it is spaced to the left from the notch 27, as shown in Fig. 9. The wall of the notch 28 circumferentially 110 nearest the notch 27 is inclined, as at 29, to provide an inclined plane, while the op-

posite wall 28' of the notch is vertical, for a purpose to be more fully hereinafter described. The flanges 25 and 26, together with their notches 27 and 28, constitute 5 clutch members. The under surface of the flange 25 is smooth and rests upon the smooth upper surface of the end of the switch operating lever 18.

Loosely mounted on the hub 24 of the 10 spool 23 is a split collar 30, see Fig. 7, the meeting ends of which are outwardly extended to form apertured ears 31. A target operating lever 32 has its inner end in the 15 form of a yoke 33. The outer end of the yoke 33 terminates in apertured ears 34 and the yoke 33 and its ears 34 embrace the split collar 30 and its ears 31, and the apertures for the ears 34 are alined to receive the bolt 35 which coöperates with the nut 35' to pivotally 20 secure the inner end of the operating target lever to the collar 30. Sufficient clearance is provided between the yoke 33 and the collar 30 to permit the necessary movement when the lever 32 is raised or lowered. On 25 the upper and lower sides of the target operating lever adjacent the inner end thereof vertical clutch lugs 36 and 37, respectively, are provided and are preferably integral with the lever 32. These clutch lugs 36 and 30 37 are adapted to engage respectively the vertical wall of the slot 27 and the vertical wall of the slot 28 to impart desired movement to the spool 23. The spool 23 is prevented from being displaced vertically by a 35 cross pin 38, which extends through the operating shaft 16 and bears against the upper side of the flange 26 of the spool.

A sleeve 39 has its lower end turned outwardly at right angles, as at 40, and bolted 40 or otherwise secured to the upper side of the flange 26 of the spool, and extends upwardly beyond the upper end of the shaft 16. The upper end of the sleeve 39 is slightly reduced, as shown at 41, see Fig. 3 and in this 45 reduced end is received and suitably secured the operating spindle 42 of the target 43. The target 43 is of conventional construction and, as usual, has its signaling face painted red. When the red face of the target 50 is so positioned that it lies in a plane at right angles to the main line so that the red face of the target is plainly visible along the main line, the target is said to be in "red" that is to indicate danger or stop. When the 55 target is so turned that the red face thereof can not be seen along the main line, it is said to be in "clear" that is in position to indicate safety or right-of-way. A loose bearing 44 is provided adjacent the upper end of the sleeve 39 to accommodate the upper end of the shaft 16. It is to be noted, however, that normally there is a clearance between the upper end of the shaft 16 and the bearing 44.

The target 43 is normally maintained in 60 danger-indicating position, and, in fact, is

always maintained in this position, except when the switch points are set for main line and the operating means for the switch points are locked in position to maintain them set for the main line. For this purpose 70 a coil spring 45 is mounted under considerable tension upon the upper end of the shaft 16. The upper end of this coil spring is seated in the shaft 16, as shown at 46, and the lower end of the coil spring is seated in 75 the sleeve 39, as shown at 47, or, if desired, may be seated in the upper face of the upper flange 26 of the spool 23. The shaft 16 is relatively stationary, and the spring 45 therefor being under considerable tension 80 and properly wound, as shown in the drawing, tends to rotate the sleeve, spool, and target spindle so that the target will be rotated to "red," that is to danger-indicating position. This tendency of the spring exists 85 at all times, and in order to maintain the target in clear, that is in position indicating safety, or right-of-way, it is necessary to positively balance this tendency. To limit the rotation of the spool, sleeve, and target 90 to danger, the lower flange 29 of the spool is provided with a radially extending projection 48, preferably formed integral therewith which coöperates with a vertically up-standing stop pin 49.

The target-operating lever 32 is arranged above the switch rod operating lever 18 and the pivoted lock arm 20, and the outer end of the operating lever 32 directly above the inner end of the pivoted lock arm 20 is provided with a cavity 50' adapted to receive the inner end of the lock arm 20 when the same is dropped into the notch 14 or 15, as the case may be. The inner end of the lock arm 20 is provided with a bolt seat 51 which co- 105 operates with the spring-projected bolt 52 of a lock 50 arranged in the outer end of the operating lever 32. The lock may be of any conventional type but is preferably adapted to be operated by the standard switch key 110 53, inserted in the key hole 53' of the lock.

Adjacent the inner walls of the cavity 50', the target-operating lever 32 is provided with a vertically depending lock plug 54, and when the lock arm 20 is in the position 115 shown in full lines in Fig. 5, with the lever 32 superposed upon the lock arm and the lever 18, the lock plug is positioned in the recess 55 defined by the under side of the lock arm 20, the inner walls of the forked 120 end 19 and the adjacent wall of the switch rod operating lever 18. When the lock arm 20 is in position intermediate the notches 14 and 15, and consequently the switch is not set for either main line or siding, the lock 125 arm 20 is alined with the operating lever 18 in the same horizontal plane and assumes the position well shown in dotted lines in Fig. 5. In this position the lock plug can not enter the recess 55 but rests upon the upper side 130

- of the inner end of the lock arm 20, whereby the target-operating lever 32 is so maintained that the projections 36 and 37 are disposed between the flanges 25 and 26 of the 5 spool 23, out of engagement with the vertical wall of either of the notches 21 or 28, thus leaving the target free to respond to the action of the spring 45 which forces it to red that is the position to indicate stop or danger.
- 10 In order to positively prevent turning of the target to the position to indicate clear until the switch has been set for main line, the switch rod operating lever 18 is provided with a vertically upstanding stop pin 56 which is adapted to engage the target operating lever 32 and prevent movement of the lever 32 past the lever 18 in the direction to actuate the target to the position to indicate clear. When the switch rod operating lever 20 15 has been moved to the position to set the switch in main line, the target operating lever 32 may be moved to actuate the target to position which indicates clear, but the target will not be maintained in this position until the lock arm 20 has been dropped or 20 swung into the slot 14, as due to the engagement of the lock plug 54 of the lever 32 with the inner end of the lock arm 20 the lever 32 is maintained between the flanges 25 and 26 25 with clutch lugs 36 and 37 out of engagement with the notches of these flanges. If, however, the lock arm 20 has been dropped into the slot 14 the lock plug 54 enters the recess 55, the lower clutch lug 37 engages the vertical wall of the notch 28 and the target 42 is maintained in position to indicate clear. At this time the switch is locked set 30 for the main line and it is only at this time that the target is maintained in clear.
- 35 40 If preferred, means may be employed to automatically disengage the target operating lever 32 and the switch rod operating lever 18 as soon as the switch lock 50 has been operated upon to withdraw the lock bolt 52 from engagement from the bolt seat 51 of the lock arm 20. For this purpose a spring 57 is disposed between the levers 18 and 22, as shown in Fig. 5. This spring may be of any type but it preferably consists of a leaf 45 spring secured at its outer end to the outer end of the lever 32 and bowed downwardly from the lever 32 so that its lower end bears against the upper face of the lever 18. As soon as the lock is actuated to withdraw the bolt the spring 57 throws the lever 32 upwardly so that the lock plug 52 is withdrawn from the recess 55 and the clutch lug 37 is withdrawn from the notch 28 thus allowing the target 42 to respond to the action of the 50 spring 45.
- 55 Any suitable housing is provided for the spool 23, and it preferably consists simply of a weather plate 58 disposed as shown in dotted lines in Fig. 1.
- 60 65 In practice the switch is normally set for
- main line, the operating levers of the switch stand being disposed as shown in Fig. 1. In order to set the switch for the siding it is necessary to actuate the lock 50 by the key 53 to withdraw the bolt 52 from engagement 70 with the seat 51 of the lock arm 20. As soon as this occurs if the spring 57 is employed the target operating lever is disengaged from the lever 18 and the lock arm 20, and the target is at once thrown to red. In any event, 75 as soon as the target operating lever 32 is raised so that the inner end of the lock arm 20 does not project into the cavity 50' and so that the lock plug 54 is withdrawn from the recess 55, the clutch lug 37 no longer engages the vertical wall of the notch 28 and the target 42 is thrown to red. The target operating lever 32 is then moved transversely across the table 12 until it strikes the stop pin 22 and in this position the lock plug 80 85 37 has moved up the inclined plane 29 so that the upper lock plug 36 is disposed within the notch 27. The lock arm 20 may then be raised and moved transversely across the table 12 to notch 15 and when the lock arm 90 20 is lowered or swung to the notch 15 the switch is thus set for siding.
- When it is desired to reset the switch to main line the lock arm 20 is raised and together with the lever 18 is moved transversely in opposite direction across the table 12 to the notch 14 and the lock arm then lowered into this notch, as shown in Fig. 95 5. The lever 32 having its clutch lug 36 in engagement with the notch 27 is then turned 100 transversely across the table to the notch 14 carrying with it the spool 23 and consequently the target 42. When the lever 32 has been turned so as to engage the lock pin 56 the target 42 is slightly passed position to indicate clear or right-of-way. As the lever 32 is dropped to position shown in Fig. 5, the clutch lug 36 moves downwardly 105 out of the recess 27 and the spring 45 then turns the target around to clear. When the target has been turned to clear its motion is arrested by engagement of the clutch lug 37 with the vertical lower wall of the notch 28, and the target is maintained in clear as long as the switch is locked set for main 110 line. It is apparent that unless the switch is set locked for main line, irrespective of the position of the switch lever, lock arm, or target lever, the target is thrown or maintained in position to indicate danger. 115
- I claim:
1. A switch stand of the character described comprising a shaft, a switch operating lever connected to said shaft, a lock arm pivoted to said switch operating lever and provided with a bolt seat, said lock arm in unlocked position forming with said switch lever a continuous, unbroken top surface and in locked position defining with said switch lever a recess, a target, spring means for 125
- 130

maintaining said target in red, a target operating lever superposed upon said switch operating lever and provided with a cavity on the under side of its outer end and a depending lock plug adjacent said cavity, a spool upon which said target lever is loosely mounted having spaced flanges provided on their inner surfaces with notches spaced circumferentially about said spool with respect 5 to each other, clutch lugs on said target lever, one of said clutch lugs being engageable with one of said notches to draw said target from red to past clear and the other of said lugs being engageable with the other 10 of said notches to maintain said target in clear when said lock arm is in locked position and said lock plug entered in the inner recess defined by said lock arm and said clutch lever, and a lock in the outer end of 15 said target lever having a spring bolt engageable with the bolt seat of said lock arm.

2. A switch stand of the character described comprising a shaft, a switch operating lever connected to said shaft, a lock arm 20 pivoted to said switch operating lever, said lock arm in unlocked position forming with said switch lever a continuous, unbroken top surface and in locked position defining with said switch lever a recess, a target, spring 25 means for maintaining said target in red, a target operating lever superposed upon said switch operating lever and provided with a cavity on the under side of its outer end and a depending lock plug adjacent 30 said cavity, connecting means operable to establish connection between said target lever and said target whereby said target may be turned to clear and maintained in clear when said lock arm is in locked position and said lock plug entered in the inner 35 recess defined by said lock arm and said clutch lever, and a lock in the outer end of said target lever having a spring bolt engageable with said lock arm.

3. A switch stand of the character described comprising a table having spaced 40 peripheral notches, a shaft, a switch operating lever connected to said switch operating lever, a lock arm pivoted to said switch lever and engageable with said notches, a target, a spool loosely mounted upon said shaft having upper and lower flanges provided on their inner faces with notches spaced circumferentially with respect to each other, means 45 connecting said target and said spool, spring means adapted to maintain said target in red, a target operating lever loosely mounted on said spool, an upper clutch lug on said target lever and a lower clutch lug on said target lever, the upper clutch lug being engageable with the upper notch to turn said target to clear and the lower clutch lug being engageable with the lower notch to maintain said target in clear, all as and for the purposes set forth.

the lower notch to maintain said target in red, and means for preventing the target lever from passing the switch lever in the direction to move the target to clear, all as and for the purposes set forth. 70

4. A switch stand of the character described comprising a table having spaced peripheral notches, a shaft, a switch operating lever connected to said shaft, a lock arm pivoted to said switch lever and engageable 75 with said notches, a target, a spool loosely mounted upon said shaft having upper and lower flanges provided on their inner faces with notches spaced circumferentially with respect to each other, a sleeve connecting said spool with said target, a coil spring mounted on said shaft and having one end secured in said shaft and the other end secured to said spool to maintain said target in red, a target operating lever loosely 80 mounted on said spool, an upper clutch lug on said target lever and a lower clutch lug on said target lever, the upper clutch lug being engageable with the upper notch to turn said target to clear and the lower clutch lug being engageable with the lower notch to maintain said target in clear, all as and for the purposes set forth. 85

5. A switch stand of the character described comprising a shaft, a switch operating lever connected to said shaft, a target, a spool loosely mounted upon said shaft having upper and lower flanges provided on their inner faces with notches spaced circumferentially with respect to each other, means connecting said target and said spool, spring means adapted to maintain said target in red, a target operating lever loosely mounted on said spool, an upper clutch lug on said target lever and a lower clutch lug on said target lever, the upper clutch lug being engageable with the upper notch to turn said target to clear and the lower clutch lug being engageable with the lower notch to maintain said target in clear, all as and for the purposes set forth. 95

6. A switch stand of the character described comprising a shaft, a switch operating lever connected to said shaft, a lock arm pivoted to said switch operating lever and provided with a bolt seat, a target, a target operating lever superposed above said switch lever and said lock arm and having a cavity in its outer end, means connecting said target lever with said target, and a lock mounted in the outer end of said target lever having a spring bolt co-operating with the bolt seat of said lock arm, all as and for the purposes set forth. 115

7. A switch stand of the character described comprising a shaft, a switch operating lever connected to said shaft, a target, a target operating lever superposed on said switch operating lever, means connecting said target lever with said target, and a stop 120

65 the lower clutch lug being engageable with 130

- pin upstanding from said switch operating lever and engageable with said target lever for preventing the movement of said target lever beyond said switch lever in a direction 5 to move said target lever to clear, all as and for the purposes set forth.
8. A switch stand of the character described comprising a table having spaced beveled notches, a shaft, a switch operating lever connected to said shaft, a lock arm pivoted to said switch lever, and engageable with said notches, a target, spring means for maintaining said target in red, a target operating lever, means connecting said target lever with said target, and a stop for preventing the movement of said target lever beyond said switch lever in the direction to move said target to clear, all as and for the purposes set forth.
- 20 9. A switch stand of the character described comprising a shaft, a switch operating lever connected to said shaft, a target, spring means for maintaining said target in red, a target operating lever, means connecting said target lever with said target and an upstanding stop pin rigid with said switch lever for preventing the movement of said target lever beyond said switch operating lever in the direction to move said target to clear, all as and for the purposes set forth.
- 25 10. A switch stand of the character described comprising a shaft, a switch operating lever connected to said shaft, a target, spring means for turning and maintaining said target in red, means for limiting the movement of the target to red, a target operating lever, and means connected to said target lever and the target.
- 30 11. A switch stand of the character described comprising a shaft, a switch operating lever connected to said shaft, a target, spring means for maintaining said target in red, a target operating lever, means for locking in engagement said target operating lever and said switch operating lever in position to maintain the switch set for main line and the target in clear, and automatic means for disengaging said target lever from said switch lever when said lock is released 50 whereby to allow said spring means to throw said target to red.
- 35 12. A switch stand of the character described comprising a shaft, a switch operating lever connected to said shaft, a target, spring means for maintaining said target in red, a target operating lever, means for locking in engagement said target operating lever and said switch operating lever in position to maintain the switch set for main line and the target in clear, and automatic spring means for disengaging said target lever from said switch lever when said lock is released whereby to allow said spring means to throw said target to red.
- 40 13. A switch stand of the character described comprising means for operating the switch, a target, means for automatically moving the target to and maintaining said target in red at all times except when the means for operating the switch is locked in position to maintain the switch set for main line, a target operating lever and means adapted to connect said lever with said target. 65
- 45 14. A switch stand of the character described comprising means for operating the switch, a target, means for automatically moving the target to and maintaining said target in red at all times except when the means for operating the switch is locked in position to maintain the switch set for main line, a target operating lever, means adapted to connect said lever with said target, and means for locking said target lever and connecting means in position to maintain said target in clear when said switch operating means is locked in position to maintain the switch set for main line. 70
- 50 15. A switch stand of the character described comprising means for operating the switch, a target, spring means for maintaining said target in red, a clutch member connected with said target, a target operating lever, and a clutch member on said lever and adapted to coöperate with said first-named clutch member for establishing connection between said lever and said target, all as and for the purposes set forth. 75
- 55 16. A switch stand of the character described comprising means for operating the switch, a target, means for automatically moving the target to and maintaining the target in red except when the means for operating the switch are locked in position to maintain the switch set for main line, operating means for said target adapted to move said target to clear and means operable to maintain said target in clear when said switch operating means is maintained in position to hold the switch set for main line, all as and for the purposes set forth. 80
- 60 17. A switch stand of the character described comprising means for operating the switch, a target, means for automatically moving the target to and maintaining the target in red except when the means for operating the switch are locked in position to maintain the switch set for main line, operating means for said target adapted to move said target to clear and means operable to maintain said target in clear, and means for preventing the operation of said last named means, except when said switch operating means is maintained in position to hold the switch set for main line, all as 115 and for the purposes set forth. 120
- 65 18. A switch stand of the character described comprising means for operating the

- switch, a target, means for automatically moving the target to and maintaining the target in red and operating means for said target.
- 5 19. A switch stand of the character described comprising means for operating the switch, a target, spring means for normally maintaining said target in red, clutch members connected with said target, a target 45 operating lever, and clutch members on said lever, one of said last-named clutch members being adapted to engage said first-named clutch members to throw said target to clear, the other of said last-named clutch members being adapted to engage the other 50 of said first-named clutch members to maintain said target in clear when said switch operating means is locked in position to maintain said switch set for main line.
- 10 20. A switch stand of the character described comprising means for operating the switch, a target, spring means for normally maintaining said target in red, a spool connected to said target and having spaced 55 flanges notched on their inner side to constitute clutch members, a target operating lever loosely mounted on said spool between said flanges, clutch lugs on the opposite sides of said lever and each engageable with the respective notch of said spool, all as and for the purposes set forth.
- 15 21. A switch stand of the character described comprising means for operating the switch, a target, a spool connected to said target and having spaced flanges notched on their inner side to constitute clutch members, a target operating lever loosely mounted on said spool between said flanges, clutch lugs on the opposite sides of said lever and 60 each engageable with the respective notch 65 70 75
- 25 30 35 40
- of said spool, all as and for the purposes set forth.
22. A switch stand of the character described comprising a table having spaced peripheral notches, a shaft, a switch operating lever connected to said shaft, a lock arm pivoted to said switch lever and engageable with said notches, a target, a spool loosely mounted upon said switch rod having upper and lower flanges provided on 50 their inner faces with notches spaced circumferentially with respect to each other, a sleeve connecting said spool with said target, a target operating lever loosely mounted on said spool, an upper clutch lug on 55 said target lever and a lower clutch lug on said target lever, the upper clutch lug being engageable with the upper notch to turn said target to clear and the lower clutch lug being engageable with the lower notch 60 to maintain said target in clear, all as and for the purposes set forth.
23. A switch stand of the character described comprising a shaft, a switch operating lever connected to said shaft, a target, a spool loosely mounted upon said switch rod having upper and lower flanges provided on their inner faces with notches spaced circumferentially with respect to each other, means connecting said target 70 and said spool, a target operating lever loosely mounted on said spool, an upper clutch lug on said target lever and a lower clutch lug on said target lever, the upper clutch lug being engageable with the upper notch to turn said target to clear and the lower clutch lug being engageable with the lower notch to maintain said target in clear, all as and for the purposes set forth.

FLOYD AUGUSTUS CANTWELL.
